UNITED STATES PATENT OFFICE

2,244,112

METHOD OF AND APPARATUS FOR
ANNEALING GLASSWARE

Donald G. Merrill, West Hartford, Conn., assignor
to Hartford-Empire Company, Hartford, Conn.,
a corporation of Delaware

Application March 2, 1936, Serial No. 66,611

29 Claims. (Cl. 49—47)

This invention relates to a method of and an apparatus for annealing glassware and more particularly to a method and apparatus for operating and constructing glassware annealing lehrs in which the temperature of the ware is controlled by generating products of combustion in the heated portion of a lehr tunnel, the products of combustion enveloping the glassware passing through the lehr, and/or in which the cooling of the glassware in the cooling portion of the tunnel is effected by the circulation of a cooling medium, such as air, in this portion of the tunnel in direct contact with the ware passing therethrough.

Among the objects of the present invention are to provide a method as aforesaid wherein substantially all the products of combustion are exhausted from the lehr through the hotter or ware-entering end thereof.

A further object is to provide a method of annealing glassware, as above set forth, in which gases are circulated in the hotter portion of the tunnel under the directive or inductive action of the burners provided in this portion for maintaining the desired temperature gradient. Specifically this circulation is of such character that sufficient heat will be distributed to the side portions of the tunnel to offset the normal cooling effect at the sides, as by circulating hot gases first toward the side walls below the path of the ware, thence up the side walls, thence toward the center above the path of the ware, and thence downwardly at the central longitudinal portion between the ware to be recirculated as aforesaid.

A further object of the present invention is to provide a method of the character above generally set forth in which a circulation of tunnel atmosphere is established in the first or entering zone of the tunnel in a direction generally longitudinal thereof, and more specifically to provide such a circulation by the inductive action of burners so arranged that at least a part of the gases are recirculated thereby and come into direct contact with the glassware.

A further object of the present invention is to provide methods of the character above set forth in which provision is made for effecting a lateral or transverse control of the temperature gradient in the tunnel in the several portions thereof, for example to compensate for a condition in which one side of the lehr might tend to run hotter than another where it is desired to maintain uniform transverse temperatures, or where the normal condition is uniform and it is desired

that unequal transverse temperatures be maintained.

A further object of the present invention is to so coordinate circulation of cooling air in the cooling end of the tunnel and inflow at such end with air exhausted in the cooling portion of the tunnel as to maintain desired pressure conditions in the heated portion of the tunnel and a desired flow, usually out of the hotter end of the tunnel.

A further object of the present invention is to provide a method for use in the type of the lehr generally set forth above for preheating the lehr when it is desired initially to put it into operation after it has been shut down for a period or for maintaining the desired temperature gradient in the tunnel during a period in which no ware is going through, or in which the rate of loading in weight of ware per unit of time is so small that the normal heat losses from the tunnel are materially in excess of the rate of supplying heat thereto with and by the ware.

A further object of the present invention is to provide a lehr structure capable of carrying out the above-mentioned methods.

A further object of the present invention is to provide means for the supplying of heat in the hotter portion of the lehr tunnel including groups of burners some, if not all, of which are arranged at acute angles to the longitudinal axis of the tunnel so that a minimum number of burner groups will provide the necessary diffused heating of a relatively long section of the lehr and specifically to provide a novel structure cooperating with the burners for establishing an induction recirculation of tunnel atmosphere as above generally set forth.

A further object of the present invention is to provide apparatus and a method for adjustably controlling the exhaust of products of combustion out of the hot or ware-entering end of a direct fired lehr in such manner that inflow of relatively cold atmospheric air into the tunnel at this end will be substantially prevented.

A further object of the present invention is to provide means for establishing a longitudinal recirculation of products of combustion and tunnel atmosphere at the entering end zone of a lehr tunnel, while at the same time providing for the diffused supplying of heat to the tunnel in this zone and preventing excessive heating at any point.

A further and specific object of the present invention is to provide a novel damper means adjacent to the forward or entering end of a lehr

tunnel for controlling the longitudinal circulation as set forth above, in such manner that a desired proportion of the gases circulated may be exhausted from the tunnel at the forward end thereof, while the remainder may be recirculated in the entering end zone of the tunnel, the control being preferably effective both as a control of the total amount of gases recirculated and also for effecting differential control thereof laterally of the tunnel.

A further object is to provide in the cooling portion of a lehr tunnel for the recirculation of a cooling medium, such as air, in this portion by the inductive action of jets and at the same time provide for the controlled exhaust of cooling medium from the tunnel selectively in zones throughout a major portion of the cooling section of the tunnel. In this connection it is a certain novel object to provide specific structure for effectively accomplishing this purpose in such manner that the structure may be easily and cheaply installed and readily controlled from outside the lehr during the operation thereof.

A further object of the present invention is to provide means by which the inflow of atmospheric air into the rear end of a lehr tunnel may be controlled in such manner that the pressure within the tunnel in the heated portion may also be controlled to control the flow through the hotter or ware-entering end thereof.

Other and more specific objects of the present invention will become apparent from a reading of the following description of a preferred embodiment thereof and from the appended claims, all when taken in connection with the accompanying drawings, in which:

Figures 1 to 7 inclusive are views principally in longitudinal vertical section which, when arranged together in numerical order, illustrate substantially the entire lehr, certain of the views being partly in side elevation;

Fig. 8 is a view, the upper portion of which is substantially in horizontal section on the line *a*—*b* of Fig. 1, while the lower portion of which is substantially in horizontal section on the line *a*—*c* in that figure;

Fig. 9 is a composite view similar to Fig. 8, but showing the portion of the lehr illustrated in Fig. 2;

Fig. 10 is a view in transverse vertical section substantially on the line *10*—*10* of Fig. 1;

Fig. 11 is a view in transverse vertical section substantially on the line *11*—*11* of Fig. 2;

Fig. 12 is a view in transverse vertical section substantially on the line *12*—*12* of Fig. 4;

Fig. 13 is a view in transverse vertical section substantially on the line *13*—*13* of Fig. 5;

Fig. 14 is a view in transverse vertical section substantially on the line *14*—*14* of Fig. 6;

Fig. 15 is a fragmentary view in horizontal section of the forward end of the lehr taken substantially on the line *15*—*15* of Fig. 1, and showing in detail the construction of the damper means at the forward end of the lehr;

Fig. 16 is a detail view of one of the burner assemblies taken in horizontal section on the line *16*—*16* of Fig. 17;

Fig. 17 is a view in vertical section of the same structure taken on the line *17*—*17* of Fig. 16;

Fig. 18 is a fragmentary view in vertical section on the line *18*—*18* of Fig. 20 showing a modified form of means usable in the cooling portion of the lehr;

Fig. 19 is a fragmentary detail view of the same

structure in longitudinal vertical section taken on the line *19*—*19* of Fig. 18; and

Fig. 20 is a fragmentary detail view of the same structure in inverted horizontal section taken on the line *20*—*20* of Fig. 18.

While I have chosen for purposes of illustration to show a lehr in which the products of combustion and the cooling air come into direct contact with the ware, it will be understood that certain phases of the invention are not limited to this type of lehr, but may be applicable even where muffled heating and/or cooling is used.

Furthermore, the present invention is somewhat similar in certain respects, especially as to the cooling portion of the lehr, to that forming the subject matter of my prior and copending application, Serial No. 54,448, filed December 14, 1935, for Method of and apparatus for annealing glassware, now Patent No. 2,133,783 granted Oct. 18, 1938. As to all subject matter common to this and my copending application, the present application is to be considered as a continuation in part of my said prior application.

The lehr illustrated in the accompanying drawings and embodying my invention is shown as constructed with a rigid frame work of structural members including longitudinally extending channel members *1*, which are connected at intervals by transverse channels *2* and *3*, and also by other suitable structural members such as the angle member *4*, Fig. 1, and the channel *5*, Fig. 5. The transverse channels *3* are somewhat larger than the channels *2*, and associated with these channels *3* are supporting members such as I-beams *6*, which serve as legs or pedestals for supporting the lehr structure from the floor or the support on which it is built. While I have shown the supports *6* bearing substantially directly upon the subjacent support or floor of the factory indicated at *7*, I contemplate that if desired, suitable means such as wheels or castors could be used to permit of the movement of the lehr as a whole. Inasmuch as such means are now common both in the patented and in the commercial art, they are not illustrated in the accompanying drawings.

Supported by the structural framework above described is a box-like casing member formed of vertical angles *8* on each side of the tunnel and transverse angles *9*, Figs. 3 and 4, above the tunnel, this entire framework holding a casing including bottom panel members *10*, side panel members *11*, and top panel members *12*, all of which are preferably of relatively thin sheet metal.

The structural members and the casing aforesaid enclose a tunnel construction including the insulation, supporting means, etc., presently to be described. As shown in Figs. 1, 3, 4, 10, 11 and 13, the interior tunnel comprises masonry blocks which support metallic belt carrying means and which are in turn supported from the external structural frame by spaced groups of pillars *13* of refractory or insulating material. These pillars are preferably located above the transverse channels *2* and *3*, there preferably being several pillars laterally of the lehr in each of the groups. In this way, I attain for my novel lehr the result of substantially complete insulation for the interior tunnel; that is, there are substantially no metallic members extending between the exterior and interior of the tunnel in the hotter portion thereof where it is desired to conserve and regulate the heat, and to maintain a desired temperature gradient.

The interior tunnel is constructed as shown in the accompanying drawings of blocks of masonry in those portions of the lehr shown in Figs. 1, 2 and 3 and up to a part of that shown in Fig. 4. These blocks may be constructed of a special somewhat porous and very light weight concrete material having relatively high insulating characteristics as contrasted with normal concrete. This material may and in practice is constructed by casting the blocks from a wet mixture of cement and a granular aggregate of calcined diatomaceous earth. As shown, the bottom is constructed of blocks 14, Figs. 1 and 10, the sides of blocks 15, Figs. 8 and 9, and the roof of blocks 16. In order to provide additional support for the roof blocks, they may be suitably reinforced as shown and provided with bracket members 17 cast therein and connected by bolts 18 with longitudinally extending short angle members 19, as shown in Figs. 1, 3, 4 and 10, suitable nuts being threaded on the bolts 18 to secure them in the desired position. The angles 19 are in turn supported by the transverse angles 9. The tunnel forming blocks may be recessed and interfitted, as illustrated in Figs. 10 and 11, to maintain them in the desired positions. Intermediate the outer metallic casing and the tunnel forming blocks 14, 15 and 16, there is preferably provided some suitable insulating material 20, which may be mineral or glass wool or some powdered material as "Sil-o-Cel" or kieselguhr. Furthermore, the side and roof blocks may be suitably positioned by the use of spacer bricks or blocks as shown at 21, Figs. 10 and 11, extending between these blocks and the metallic outer casing and preferably resting on suitable angle brackets secured to that casing.

Within the tunnel so formed, there is provided in the heated section of the lehr, which in the present instance is that portion down to and including the structure shown in Figs. 1, 2 and 3, and a small part of Fig. 4, certain means for supplying heat to the tunnel, which will be separately described. Also in the cooling portion of the lehr, i. e., that portion beginning substantially at the center of the part of the lehr shown in Fig. 4 and continuing through the remainder of the length of the tunnel, there are means for abstracting heat from the ware, which also will be more particularly described herein-after.

Throughout the lehr tunnel, the ware is carried upon an endless conveyor belt 22, which is preferably of open-work woven wire material having its ware-bearing strand supported, as more specifically hereinafter set forth, and passing through the tunnel and its idle strand returning to the entering end of the tunnel beneath the same. After passing out of the exit end of the tunnel, as shown best in Fig. 7, the conveyor 22 passes across a packing table, generally indicated at 23, and thence passes through a driving mechanism generally indicated at 24. Inasmuch as the conveyor driving means is substantially conventional and is more specifically illustrated and described in the Mulholland Re-issue Patent 17,263, granted April 9, 1929, and Mulholland Patent 1,560,481, granted November 3, 1925, it will not be described in detail, but reference may be had to the Mulholland patents for a specific description thereof.

For supporting the conveyor, I preferably provide a structure permitting the circulation of gases about all sides of the ware in paths passing through the conveyor and its support. In the heated portion of the lehr, this conveyor

support may be prefabricated in removable units of a given length and such units removably placed in position and secured at the desired positions in such manner that provision is made for each unit to expand independently of the other units, rather than for the whole conveyor support to expand as an entity.

In Figs. 1, 10 and 11, there is illustrated a part of this conveyor support which may be built up of longitudinally extending channels 25 to which may be secured as by welding, or in any other desired manner, transverse angles 26 upon which the conveyor is directly supported. This structure is further rigidified by securing as by welding, or in any other suitable manner, at the edges thereof Z-bars 27 having upwardly extending flanges for positioning the conveyor against lateral displacement and downwardly extending flanges cooperating with adjacent refractory blocks in the tunnel for positioning the conveyor support. The several units or sections of the conveyor support are suitably carried by the subjacent refractory structure, as hereinafter to be set forth, and extend substantially up to the point 28, Fig. 4, that is, throughout the heated portion of the lehr. Suitable means (not shown) may be provided for accurately positioning the conveyor support against longitudinal movements with the conveyor upon movement thereof and for securing the various sections together.

The remainder of the conveyor support and the inner tunnel throughout the cooling portion thereof may be constructed substantially as a unit, that is, after it has been assembled and suitably secured together. As shown, the bottom of the inner tunnel in this portion is formed by a plate 29, which may be of sheet metal, to which are secured a plurality of laterally extending channels 30 which support the conveyor, there being suitable relatively thin spacer strips 31 positioned above each of the channels 30 as shown in Figs. 4, 5 and 6. Along both sides of the tunnel there are secured to the channels 30 longitudinally extending angles 32, Figs. 12, 13 and 14, for guiding the conveyor 22.

This rigid construction is anchored against movement longitudinally of the lehr at but one point and is permitted to expand in both directions from this point. For this purpose, there is provided as shown in Fig. 4 transverse angles 33 secured to the under side of the bottom plate 29 and adapted loosely to straddle a transversely extending I-beam 34, which is suitably secured to the external frame structure of the lehr, specifically the side channels 1. The integral tunnel construction provided in the cooling section of the lehr may expand to some extent with respect to its supports, but this will not interfere with the desired operation, due to the fact that the expansion and contraction in this cooling portion of the lehr is relatively small as the temperatures are comparatively low in this part of the lehr.

At the forward or ware-entering end of the lehr, there is preferably provided a vertically movable door generally indicated at 35 (Figs. 1 and 8), this door structure being similar to that described in detail in the Wadman Patent 1,974,058, granted Sept. 18, 1934 (see Figs. 9 and 10 thereof and the associated description). It will be understood that this door may be manually adjusted to any desired height so as to clear articles which are being annealed and also may, if desired, be closed for heating the lehr or during any period when articles are not being

moved thereinto through the entering end thereof, as particularly set forth hereinafter. Inasmuch, however, as the construction and mounting of the door per se form no part of the present invention, they will not be further described.

Front end heating and recirculating means (Figs. 1, 8, 10 and 15)

I preferably provide means at the first or entering end zone of the tunnel for supplying a substantial amount of the total heat supplied to the tunnel, as this is the place where the maximum amount of heat is normally required, as to bring cool ware up to the desired temperature, to offset losses of heat through the entering end of the tunnel and to preheat the conveyor, etc. I also provide for the recirculation of at least a part of the products of combustion supplied to this zone in directions generally longitudinal of the lehr and also in such manner that the velocity effect of the gases tends substantially to prevent inflow of relatively cold atmospheric air into the hotter or entering end of the tunnel.

As shown, there are arranged below the path of the ware and at a predetermined line spaced from the entering end of the tunnel, a plurality of burners 36. These burners are preferably arranged as shown in two groups, one on each side of the longitudinal center line of the lehr and are arranged so that each group may be controlled independently. For this purpose, the two lower burners 36, as seen in Fig. 8, are connected to a common supply pipe 37 while the two upper burners are similarly connected to a common supply pipe 38. The pipes 37 and 38 are provided outside the lehr with couplings 39 and with valves 40 and 41 for the pipes respectively, on the upstream side of the couplings. Thus, by the manipulation of valves 40 and 41, the supplying of combustible medium through the groups of burners 36 may be controlled jointly and severally. The provision of the couplings 39 permits of the removal of the burners 36 with their pipes 37 and 38 for purposes of cleaning, replacement or repair.

The burners 36 are preferably supplied with a combustible mixture of gas and air from some suitable mixing device (not shown), the velocity of flow through the burners 36 being greater than that of flame propagation through the mixture, so that the flame will not snap back and burn in the supply pipes. Inasmuch, however, as the burners themselves are commercial products and do not per se form a part of the present invention, their detailed construction has not been illustrated and will not be described.

Opposite each of the burners 36, there is provided as shown a burner block 42, which is dome-shaped, as best seen in Fig. 10, and is provided with an aperture aligned with that of the burner through which the combustible medium passes. The burner blocks 42 are smaller than their associated passages to provide for the induction circulation of air and products of combustion as hereinafter set forth. Each of the burner blocks 42 is located substantially at the entrance end of a Venturi passage 43, the bottom of which is formed by one of the blocks 14 forming the tunnel bottom. The sides of these Venturi passages are formed by vertical walls built up upon the blocks 14, as best seen in Fig. 8, and the tops are formed in part by a plurality of refractory tile members 44 adjacent to the constricted part of the Venturi passages 43 and in part by a plu-

rality of metallic heat radiating members 45, there being four of these members in the construction shown. The members 45 are loosely placed in position to leave spaces between and around them so as to permit them to expand when the structure is heated. These members are provided with a plurality of longitudinally and transversely extending ribs as illustrated, which serve the purposes of providing rigidity for the members, and tending to prevent their warping, of carrying the conveyor supporting structure, and of assisting in diffusing the heat from the flames in the Venturi passages 43, which heat is absorbed by the members 45, conducted therethrough and radiated to the ware passing thereabove on the belt 22.

At the forward end of the lehr the several Venturi passages 43 merge into a common passage, which is open both to the interior of the tunnel in advance of the first of the members 45 and also to the exterior of the tunnel in advance of the front door 35 thereof. For deflecting the gases upwardly at the front end, there is formed in this passage an insert portion 46, which may be of refractory material and is constructed so that the velocity effect of the gases passing upwardly, some back into the lehr and the remainder out the front end thereof, will serve substantially to prevent inflow of relatively cold atmospheric air into the tunnel at this point. Above this exhaust port out of the tunnel in advance of the front door and in a position to support the conveyor 22 passing across this port is a perforated plate 47, Figs. 1 and 8. This exhaust port may further be provided with suitable division walls, as best shown in Fig. 15, including a transverse wall 48 and longitudinal walls 49, so that there is formed a plurality of compartments or partial ports through which the gases may pass in exhausting from the lehr at the front or entering end thereof.

Associated with each of these partial ports is an independently adjustable damper, as shown in Fig. 15 at 50, 51, and 52 respectively. Fig. 8 may be considered to be diagrammatic as to these dampers and shows them as a single damper generally indicated at 53 in that figure. It will be understood, however, that while I prefer to use a plurality of dampers at this point, as shown in Fig. 15, to obtain an additional function therefrom as hereinafter set forth, the device is operative for many purposes with but one damper as shown at 53 in Fig. 8 extending all across the lehr and without the dividing walls 48 and 49, as shown in Fig. 15.

The function of the dampers 50, 51 and 52 is collectively to control the proportion of the products of combustion passing through the Venturi passages 43 which is deflected back into the lehr tunnel to move in the same direction as that of the movement of the ware therethrough and the complementary proportion which is exhausted through the perforations in the plate 47 outside the lehr tunnel at the forward end thereof. Another effect of these dampers is that when the dampers are in a position so that a substantial part of the gases are exhausted from the lehr, such as the adjustment illustrated in Fig. 1 for example, the ware will come under the influence of lehr temperatures in advance of the time it would come under the influence of these temperatures if it had to pass inside the tunnel before being bathed in an atmosphere of hot gases and subjected to the temperatures in the tunnel.

Also, if all the dampers 50, 51 and 52 are

maintained at the same adjustment, there will be a substantially uniform deflection of gases backward into the tunnel. On the other hand, if the dampers are differentially adjusted as illustrated in Fig. 15 for example, differential temperature gradients may be maintained transversely of the lehr especially in conjunction with differential adjustment of the supplying of heat transversely of the lehr by differential control of the amount of combustible medium passing through the pipes 37 and 38 under control of valves 40 and 41.

This differential transverse control in conjunction with similar controls in other portions of the lehr, hereinafter to be described, may be effective in practice to maintain uniform transverse conditions which would not otherwise exist, such for example as in the case of an installation, one side of which is closely adjacent to hot bodies, such as the checkers of a glass melting furnace, while the other side is open to radiate to the cooler outside walls of a factory. Here the side of the lehr toward the furnace would tend to run hotter than the other side and it might be necessary to resort to some special regulation, such as is available in the lehr of my present invention, in order to establish transverse uniformity of temperatures. On the other hand, in the event that the lehr is being used to anneal ware from two forming machines which is dissimilar as to weight or type, one type of ware being placed on one side of the longitudinal center of the lehr conveyor while the other type is placed on the other side, then it may be desired to establish non-uniform transverse condition in the lehr tunnel, which also is possible with apparatus constructed in accordance with my present invention and operated according to the methods thereof.

For effecting a practical control of the position of dampers 50 to 52, each of these dampers is connected by a loose connection at 54, with a thrust rod 55 passing through a suitable sleeve through the refractory insert portion 46 and connected outside the lehr with a transverse adjusting bar 56 (Fig. 15). This bar is designed to be adjusted in such a way as to adjust the dampers 50 to 52 simultaneously and also differentially. For this purpose the bar is provided at each end with a pin as shown at 57, Fig. 15, each of which pins is adapted to enter any one of a plurality of holes in a pair of curved brackets 58. By suitably positioning the two ends of the bar 56 in respect to the brackets 58, the dampers 50 to 52 may be adjusted in any desired manner.

In normal operation the velocity effect of the flames and products of combustion from the burners 36 will induce a material flow of tunnel atmosphere passing downwardly from the tunnel through the conveyor and between the members forming the conveyor support to the region adjacent to the burners 36. This gaseous media with the newly generated products of combustion will flow through the passages 43 and a part will be discharged out the forward end of the lehr through the perforations in the plate 47, the remainder being returned to the lehr tunnel to flow longitudinally thereof in the same direction as the movement of the ware therethrough and to be recirculated in part at least by the burners 36.

The principal heated zone of the lehr (Figs. 2, 3, 9 and 11)

In the zone of the lehr following that just described in detail and extending approximately 25

feet in a normal length lehr, there is provided means for supplying heat to the lehr for maintaining a fairly high temperature and for controlling the temperature gradient of the glass in passing through its critical annealing range. During this period in the annealing of the glass, it is normally desired that the temperature drop very gradually, so that permanent strains will be removed and kept out of the ware to the end that the desired character of annealing will take place. The rate of heat dissipation through the outside of the tunnel in this zone is usually slightly greater than the amount of heat which is normally to be dissipated from the ware in passing through the zone, so that means are normally provided for supplying heat to the tunnel in this zone to make up the difference. However, in annealing average weight articles at an average rate, this difference is not very great so that the amount of heat which must be supplied is not large. On the other hand, it must be supplied in such a manner that fairly uniform temperatures exist throughout the zone, but with the desired temperature gradient downwardly superimposed upon the above-mentioned uniformity. For this purpose, it is desirable that heat be fairly evenly diffused in different parts of the tunnel which is one of the results obtained by the construction presently to be described.

It has been proposed heretofore to provide a plurality of burners each substantially independently controllable in order to obtain a desired temperature gradient throughout a heated zone. However, if no special provisions to made for diffusing the heat from the burners, it is usually necessary to provide a relatively large number of burners and space them fairly close together. By my novel provisions, I am enabled to attain the desired temperature conditions using a relatively few groups of burners spaced at considerable distances apart, the heat from these groups being diffused along the tunnel to obtain a smooth temperature gradient.

As shown in the accompanying drawings, there are a plurality of burner groups, in the present instance six, provided intermediate the forward burners 36 described hereinabove and the point 28, Fig. 4. Inasmuch as each of these burner groups and the associated flame passages are similar to the others, only one will be described.

Each burner group comprises a burner assembly 59, Fig. 3, the details of which are shown in Figs. 16 and 17 and will be hereinafter described. This burner assembly includes four jet-type burners directed at substantially 90° angles to one another and all being disposed so as to supply flames in a substantially horizontal plane, generally toward the sidewalls of the tunnel below the path of the ware therethrough, and specifically at acute angles to the longitudinal axis of the tunnel, substantially 45° in each case. The burner assembly 59 is rigidly carried by the two supply pipes 60 and 61, which are provided outside the lehr with couplings 62 and valves 63 and 64 for the pipes 60 and 61 respectively. Thus the pipes 60 and 61 may be disconnected from their supply pipes, once the supply therethrough is shut off, so as permit the removal of the burner assembly for cleaning, replacement or repair.

Referring now to Figs. 16 and 17, wherein I have illustrated in detail the interior construction of one of the burner assemblies 59, each of these burner assemblies comprises a metallic casting 65, including two chambers 66 and 67. Each of these chambers has associated therewith

two nozzle members 68 and 69 for chamber 66 and 70 and 71 for chamber 67. The burner is located in its operative position for use with nozzle members 68 and 69 directing flame toward one side of the longitudinal center of the lehr while nozzle members 70 and 71 direct flame toward the other side thereof. Combustible media for supplying nozzle members 68 and 69 are conducted to chamber 66 through pipe 60, as best seen in Fig. 16, while combustible media for the other two nozzle members are conducted to chamber 67 through pipe 61. Thus by the independent control of valves 63 and 64, I am enabled to obtain a differential temperature control for the two sides of the lehr for the purposes and with the advantages above set forth.

Around the casting or metallic member 65 is a refractory housing 72, which serves to protect the metallic portions of the device from the relatively high heat existing in this part of the lehr construction. Also, each of the nozzle members 68 to 71 has associated therewith a refractory burner block 73 which functions in the usual manner. The interior construction of each of the nozzle members 68 to 71 forms no part of the present invention and hence will not be described. These nozzle members may be and preferably are products available for purchase on the open market.

Means are provided as above set forth for locating the burner assembly 59 in the desired position and also for facilitating the removal thereof when such removal is desired. As best shown in Figs. 11 and 17, the burner assembly 59 is provided with a projection or stud 74 adapted to fit into a recess 75 formed in the bottom block 14 at the desired point for locating the burner assembly at its operative position. The burner assembly 59 is carried as above set forth by the pipes 60 and 61 which, as shown in Figs. 16 and 17, are threaded into the metallic casting 65 for this purpose. The pipes 60 and 61 pass toward the side of the lehr in a channel formed between blocks 76 and pass through a block 77 (Fig. 11), this block being provided with suitable bores for this purpose. Above the block 77 there is located a removable block 78, which is held in position by an outer movable cover member 79, Fig. 2. Thus, when it is desired to remove the burner assembly, the couplings 62 are disconnected, the cover 79 and block 78 are then removed, and the burner assembly may then be tilted upwardly by tilting the pipes 60 and 61 in a clockwise direction, as seen in Fig. 11, to displace the stud 74 from the recess 75. The burner assembly 59 may then be drawn out of the lehr by the pipes 60 and 61 and cleaned or repaired and replaced, or a new burner substituted therefor. The installation of a burner assembly may be accomplished by carrying through a reverse series of steps from that just described.

Located above the block 78 at a desired point is a block 80 provided with a peep hole 81 there-through which registers with a hole 82, Fig. 2, in the outer casing 11 of the lehr, this hole serving for the purpose of permitting observation of all the flames from the burner assembly 59 associated therewith. Thus it can be determined by inspection whether the burner is operating properly and/or whether it needs to be removed for cleaning or repair.

Turning now to the arrangement of the flame and gas passages beneath the path of the ware through the lehr tunnel and referring particu-

larly to Fig. 9, it will be seen that aligned axially with the burner nozzles 68 to 71 are burner blocks 83 similar to the burner blocks 42 described, and mounted upon the floor blocks 14 of the tunnel. Flame passing through these blocks 83 must pass between the forward ends 84 of the adjacent blocks 76 and the curved portions of blocks 83 to a passage generally indicated at 86, the bottom of which is defined by the floor blocks 14 of the tunnel, one side by the block 76 and the other side by portions of blocks 85 and blocks 87 and 88. The remaining blocks at this level of the tunnel are end blocks 89 connecting the ends of adjacent blocks 83 and supporting blocks 90 located substantially parallel to the blocks 89 and serving only as supports for the blocks thereabove. Above these several blocks are located blocks 91 adjacent to the burners, blocks 92 in the rear thereof, large cover blocks 93 and short end blocks 94 above portions of the blocks 76, and intermediate cover blocks 95, all as shown in Fig. 9. These blocks are all of refractory material and are suitably laid in place and, if desired, secured in place by cement as at 96, filling cracks or joints therebetween. These several cover blocks 93, 94 and 95 define between themselves and the side blocks 15 elongate openings 97 through which the products of combustion from the passages 86 may pass upwardly adjacent to the side walls of the tunnel to be circulated in direct contact with the ware passing therethrough. It will be noted that the blocks 91, 93 and 94 at the upper level and blocks 76 therebelow define channels leading to each side of the lehr and a substantially circular opening directly above the burner assemblies 59 so arranged as to permit the downflow of tunnel atmosphere to the region adjacent to the burner assemblies 59 where it may be recirculated by induction as more specifically to be hereinafter set forth. Also these laterally extending channels permit of the inspection of the burners through the peep holes 81 and 82 and permit of the burners being installed with the pipes 60 and 61 leading to either side of the lehr, whichever may be the more convenient in the installation to be made.

The flames from the burner assemblies pass first through the burner blocks 83, then through the constricted portion of the channel, then the larger portion 86 thereof, and thence to the side walls and upwardly through the openings 97 to flow upwardly along the side walls of the tunnel, thence toward the middle above the path of the ware, and thence downwardly between the articles being annealed to be recirculated by the inductive action of the burners. Thus, the heat from the burners will be effective primarily to supply heat adjacent to the side walls and to maintain these portions of the tunnel at the desired temperatures, thus opposing the normal loss of heat through the side walls and the tendency in substantially all prior art lehrs for the temperatures to be lower adjacent to the side walls than in the center portions of the tunnel. In this way, I am enabled to obtain a greater uniformity in temperature than is possible with most prior constructions.

70 Cooling section of the lehr

As shown in Fig. 4, there may be provided intermediate the heated section proper of the lehr terminating substantially at the point 28 and the cooling section proper which begins substantially at the point 98 in that figure, an

intermediate section which may be neither heated nor cooled. The construction of this section has previously been covered in describing the general construction of the lehr as a whole. The section from the point 98, Fig. 4, to the exit end of the tunnel, may be considered as the cooling section of the lehr, and in this section means are provided for controlling the abstraction of heat from the ware and accelerating the cooling thereof in several zones longitudinally of this cooling section.

Extending substantially throughout the cooling section of lehr and adjacent to the upper corners of the tunnel above the path of the ware are longitudinally extending pipes 99, Figs. 4, 5, 6, 7, 13 and 14, these pipes being secured in position in a suitable manner as by hangers 100, Figs. 6 and 13, secured to the roof of the tunnel. Cooling air may be supplied to the pipes 99 by a blower 101 which may be of the centrifugal type as shown and driven by any suitable source of power (not shown). The blower 101 has a centrally located intake opening 102 and a tangentially arranged exhaust passage 103 associated therewith, flow through this passage being controlled by a suitable damper adapted to be adjusted by a hand lever 104 in the usual manner. The pipe or passage 103 divides into two passages 105 (Figs. 6 and 14) which passages communicate with the pipes 99 respectively. If desired manually adjustable dampers 106 may be interposed in the pipes 105 for permitting a relative lateral control of the cooling effects hereinafter described.

Disposed at spaced intervals along both pipes 99 are jet nozzles 107 and 108, the former directing air substantially at right angles to the axes of the pipes 99 and the latter, inclined thereto in order to direct jets of air under relatively high pressure toward the forward or ware-entering end of the lehr, so as to obtain an induction inflow of air into the exit end of the tunnel, as hereinafter to be described. In practice, the arrangement is preferably such that the jet nozzles 107 and 108 may be interchangeably threaded into the pipes 99, the nozzles themselves being of two different kinds, some (107) straight and others (108) inclined, so that any desired proportion of each may be supplied with a given construction. The usual arrangement is one in which the inclined nozzles 108 are employed adjacent to the exit end of the tunnel and the straight nozzles 107 are employed throughout the remainder of the lengths of the pipes 99.

Throughout the major portion of the cooling section as above set forth, there is a longitudinally extending deflector generally indicated at 109 located adjacent to the center portion of the roof of the tunnel, this deflector serving also as a hollow duct to assist in the exhaust of tunnel atmosphere through exhaust ports leading upwardly therefrom through the roof of the tunnel. For purposes of effecting a zone control of cooling, the interior of the deflector 109 is in effect divided into a plurality of zones, or it may be formed as specifically illustrated herein in separate portions with bridging members as illustrated at 110 therebetween so as to make a substantially continuous deflector. It will be understood that throughout the length of this substantially continuous deflector 109 the circulated air in the tunnel including the air supplied through the jets 107 or 108 and the air induced to flow thereby will impinge against the inclined lateral sides of the deflector 109 and be directed down-

wardly through the ware on the conveyor adjacent to the longitudinal center line of the tunnel, thence it will flow laterally toward the side walls of the tunnel and thence upwardly to be recirculated by the inductive action of the jets. In this respect the present construction is somewhat similar to that of my prior copending application, now Patent No. 2,133,783 above referred to.

10 Inasmuch as the construction and functioning of the cooling air recirculation in certain of the zones is somewhat different from that in others, these zones will be considered independently to a certain extent. The first zone includes that portion of the tunnel beginning substantially at the point 98 in Fig. 4 and continuing to approximately the point 111 in Fig. 5. The recirculation in this zone and the control of the exhaust of tunnel atmosphere therefrom is all under a single common control as hereinafter set forth.

Specifically the deflector members shown at 112, Figs. 4, 5 and 13, forming a part of the deflector 109 in this zone are constructed with closed ends 114 and 115 and are rigidly connected 15 to the roof plates 116 by brackets 117, Fig. 13. The inclined side walls 118 of this portion of the deflector are spaced from the roof plates 116 to provide elongate narrow openings 119 through which a part of the circulated air may pass into the interior of the duct and thence flow to an outlet port 120. In this outlet port, there is shown a plurality of dampers 121 and 122 mounted on horizontal axles, which are provided with crank arms 123 and 124 connected by a link 125 20 for common control. The damper 122 has its axle 126 extended to the side of the lehr, journaled in a bearing 127 and terminating in a handle 128 by which the setting of both dampers may be simultaneously controlled. Thus in this 25 zone a predetermined adjustable portion of the air circulated under the inductive action of the jets 107 will be caused to pass through the openings 119, along the interior of the duct formed within the deflector members 112 and out the 30 port 120 under the control of the dampers 121 and 122.

Following the zone just described and extending toward the exit end of the lehr, there are a plurality, in this case six, of similar independent cooling zones, although it will be understood of course that as many as desired could be provided. Inasmuch as these zones and the construction and control thereof are the same, only one will be described.

55 Each of these independent zones includes a deflector member 129, which is closed at its ends and forms part of the general deflector 109 in conjunction with the bridging portions 110, the deflector members 129 being secured to the top plate 12 or 116 of the tunnel by brackets 130, as best shown in Figs. 5 and 6. Thus the middle portion of the deflector 129, which is rigidly secured to the top of the tunnel as aforesaid will serve to deflect the circulated air from the jets 107 or 108, as above set forth. The deflector members 129, however, terminate a material distance short of the roof of the tunnel at each side and in these openings there are located adjustable deflector portions 131, which are pivoted to the edges of the deflector 129 at 132 (Fig. 14). When the adjustable portions 131 are substantially closed as shown in Fig. 14, they constitute substantial continuations of the inclined side faces of the deflector 129. When they are opened to some extent, however, they provide openings

similar to the openings 119, Fig. 13, between themselves and the top plate or roof of the tunnel to permit a part of the circulated air to flow to the interior of the deflector member 129 and thence out through the open port 133 associated therewith to the atmosphere.

Means are provided for controlling the angular positions of the adjustable members 131. While I have shown means for adjusting these two portions simultaneously, or in effect a common adjusting means, it will be understood that if desired, some independent adjusting means may be used. As shown, each of the adjustable members 131 has an arm 134 rigidly connected thereto, these arms being connected by links 135 to cranks 136 secured to a transversely extending shaft 137, which is journaled in the sides of the member 138 forming the exhaust port 133, and also in a bracket 139 and which terminates at one side of the lehr in a hand crank 140. Thus by the adjustment of the crank 140, both adjustable portions 131 will be simultaneously moved to the desired position to provide for the exhaust of a selected amount of air in each of the cooling zones respectively.

In general the operation of the cooling portion of the lehr is as follows. Air is supplied under relatively high pressure to the pipes 99 from the blower 101 and is directed into the lehr through jet nozzles 107 and 108, the nozzles 108 being inclined away from the cooler end of the lehr not only to cause circulation in the cooling portion thereof in generally helical paths, moving downwardly at the longitudinal center portion of the lehr toward the sides and thence up the sides to be recirculated, but also to cause an inductive inflow of atmospheric air into the exit end of the lehr, which flows countercurrent to the ware and serves to cool it, being recirculated progressively by the inductive action of the jets as it passes toward the hotter end of the lehr. The several dampers controlled by the handles 140 and 128 are so adjusted that selected amounts of the cooling air are withdrawn or discharged from the lehr at intervals along the cooling portion thereof, so that the cooling effect normally becomes progressively less toward the hotter end thereof and also the amount of air being circulated in the lehr tunnel is normally less toward the latter end, although this last may not always be the case. This results in the air being at progressively higher temperatures toward the hotter end of the lehr, so that the ware is never subjected to direct cooling action of air at temperatures too widely different from its own temperature, which might result in undue stresses being set up and possibly breakage of the ware. In effect, therefore, the control effected by the several dampers serves to control the amount of inflow of atmospheric air into the exit end of the lehr tunnel and hence the pressure existing not only in the cooling portion of the tunnel, but also to a major extent in the heated portion thereof. Thus in practice, it is feasible by this regulation to control the inflow of air at the cooling end and the pressures existing substantially throughout the lehr to the end that the exhaust of gaseous media at the entering end of the lehr is effectively controlled.

Another way in which the inflow of air at the cooler end of the lehr may be controlled to control the pressures thereof in the tunnel and flow of air through the hotter or entering end of the lehr is by apparatus constructed substantially as shown in Figs. 18, 19 and 20, in which the

5 pipes 99a correspond generally to the pipes 99, except that they are provided in the portion shown at least only with jet nozzles 107, which are positioned with their axes at right angles to the longitudinal axes of the pipes 99a, and also the pipes 99a are swivelly mounted both as to their support, the brackets 100a in respect to the lehr tunnel, and also as to their supply duct, i. e., their connection with the pipes 105. Substantially opposite each of the nozzles 107 and extending from the deflector member 109a, corresponding generally to the deflector 109, is a laterally extending inclined deflector vane 141, which may be formed substantially as shown in Figs. 18 to 20. Thus if the pipe 99a is rotated through a small angle about its longitudinal axis, the deflector nozzle 107 associated with the vane 141 will be moved in such manner that the flow of air induced thereby will be in one direction or the other longitudinally of the lehr tunnel. If some adjustment be made intermediate the extreme adjustments, the velocity of flow in one direction as from the exit toward the entrance end of the tunnel may be varied, with the desirable results above set forth. I contemplate that either or both these arrangements for controlling flow and pressure along the tunnel may be used as may be desired.

30 In the normal operation of the lehr, i. e., with average and also with relatively heavy loadings, it will not be necessary to carry heat toward the exit end of the tunnel beyond the end of the heated zone, as above set forth. Under such circumstances, therefore, I desire that substantially all 35 the products of combustion be exhausted from the tunnel through the forward or entering end thereof. It will be understood, of course, that these products of combustion may be recirculated several or many times within the tunnel, but that 40 the total amount exhausted at the forward or entering end will be at least as great as the input of products of combustion into the tunnel by all the burners at any one time. Thus, in the zone intermediate the heated and cooling zones, i. e., 45 from the points 28 to 98, Fig. 4, there will be no flow toward the exit end of the tunnel. In this intermediate zone there may at this time be a slight flow toward the entrance end of the tunnel due to the fact that the amount of air drawn into 50 the exit end of the lehr, plus the amount blown into the tunnel by the blower 101, may be slightly greater than the amount exhausted through the several exhaust ports. This tendency for air to flow through the tunnel from the exit toward the 55 entrance end may be assisted by inclining the tunnel a small amount downward toward the exit end thereof.

When, however, quite light loadings are used (in weight of glass loaded per unit of time), or 60 when no ware is being supplied to the lehr, the heat losses therefrom through the side walls will be in excess of the heat supplied in the cooling section of the lehr. Under these circumstances, it is desirable that heat be supplied to this cooling section to maintain it up to the desired temperatures. Under these circumstances, the positive cooling may be reduced or cut off completely as 65 by closing the damper 104 or stopping the blower 101, the outflow through the forward end reduced or cut off as by controlling dampers 50 to 52, and a part or all the products of combustion caused to pass toward the exit end of the tunnel and be exhausted through the ports 120 and 133 normally used for the exhaust of cooling air. This 70 has been found also to be an excellent way of

preheating the lehr before putting ware thereinto, or maintaining it with the desired temperature gradient therein during a period of time in which no ware is being passed thereinto. Under these circumstances, the front door is usually closed and some closure (not shown) may also be placed at the rear or exit end of the tunnel. The construction and all of these methods of operation are to be considered as within the purview of my invention.

While I have shown and described but one principal embodiment of my invention, and certain modified forms of a minor detail thereof, I contemplate that various changes may be made therein, both as to method and structure, including those suggested herein. I do not wish to be limited, therefore, except by the scope of the appended claims, which are to be construed as broadly as the state of the prior art permits.

I claim:

1. The method of annealing glassware, which comprises the steps of passing the ware to be annealed through an elongate lehr tunnel having a heated section and a cooling section, generating products of combustion in the heated section of the lehr tunnel in such manner that the products of combustion will envelop the ware passing through the tunnel and will flow in the tunnel to the end thereof through which the ware enters, and venting all said products of combustion to the atmosphere at said end.

2. The method of annealing glassware, which comprises the steps of passing the ware to be annealed through an elongate lehr tunnel having a heated section and a cooling section, generating products of combustion adjacent to the heated section of the tunnel, and recirculating the products of combustion in the heated section of the tunnel by energy derived at least in part from the velocity of the gases introduced into the tunnel and in such manner and direction that the recirculated gaseous media in the tunnel flow toward the sides of the tunnel at a level below the path of the ware, thence up the sides of the tunnel, toward the center thereof above the path of the ware, and thence downwardly through the path of the ware and spaced from the sides of the tunnel to be recirculated.

3. The method of annealing glassware, which comprises the steps of passing the ware to be annealed through an elongate lehr tunnel having a heated section and a cooling section, generating products of combustion in the heated section of the lehr tunnel by introducing a combustible medium into the tunnel through burners and in such manner that the products of combustion will envelop the ware passing through the tunnel, and causing a circulation of the tunnel atmosphere and the products of combustion in the heated section of the tunnel by the inductive action of the burners and in such manner and direction that the flames are directed toward the sides of the tunnel at a level below the path of the ware, the gases circulating thence up the sides of the tunnel, toward the center thereof above the path of the ware, and thence downwardly through the path of the ware and spaced from the sides of the tunnel to be recirculated by the inductive action of the burners.

4. The method of annealing glassware, which comprises the steps of passing the ware to be annealed through an elongate lehr tunnel having a heated section and a cooling section, generating products of combustion in the heated section of the lehr tunnel by introducing a combustible

medium into the tunnel through burners and in such manner that the products of combustion will envelop the ware passing through the tunnel, causing a circulation of tunnel atmosphere and products of combustion in the heated section of the tunnel by the inductive action of the burners in such manner and direction that the flames are directed toward the sides of the tunnel at a level below the path of the ware, thence upwardly,

5 10 15

thence toward the center of the tunnel above the path of the ware and thence downwardly to be recirculated by induction, and independently controlling the temperature gradients for ware passing through the tunnel on opposite sides of the longitudinal center of the tunnel by independently controlling the characteristics of the circulated gaseous media transversely of the tunnel.

5. The method of annealing glassware, which comprises the steps of passing the ware to be an-

nealed through an elongate lehr tunnel having a heated section and a cooling section, supplying heat to the heated section of the lehr tunnel, recirculating tunnel atmosphere in an orbital path wholly within the lehr tunnel in a zone starting at the entering end thereof and in a direction generally longitudinal of the tunnel, and recirculating tunnel atmosphere in a succeeding zone of said heated section of the tunnel in an orbital path wholly within the heated section of the lehr tunnel and in a direction generally transverse of the tunnel.

6. The method of annealing glassware, which comprises the steps of passing the ware to be annealed through an elongate lehr tunnel having a heated section and a cooling section, generating products of combustion in the heated section of the lehr tunnel by introducing a combustible

35 40 45 50

medium into the tunnel through the burners and in such manner that the products of combustion will envelop the ware passing through the tunnel, recirculating tunnel atmosphere including a part of said products of combustion in an orbital path wholly within the lehr tunnel in a zone starting at the entering end thereof and in a direction generally longitudinal of the tunnel by the inductive action of certain of the burners, and recirculating tunnel atmosphere including a portion of the products of combustion in an orbital path wholly within the lehr tunnel in a succeeding zone in the heated section thereof and in a direction generally transverse of the tunnel by the inductive action of certain other of the burners.

7. The method of annealing glassware, which comprises the steps of passing the ware to be an-

nealed through an elongate lehr tunnel having a heated section and a cooling section, generating products of combustion in the heated section of the lehr tunnel in such manner that the products of combustion will envelop the ware passing through the tunnel, causing the introduction of air into the cooling section of the lehr tunnel, venting air from the cooling section of the lehr tunnel to the atmosphere, and controlling the relative amounts of air introduced into and vented from the cooling section of the lehr tunnel in such manner that substantially all the products of combustion generated in the heated section of the lehr tunnel will pass along inside the tunnel to the end thereof through which the ware enters and be vented from the tunnel to the atmosphere at said end.

8. The method of annealing glassware, which comprises the steps of passing the ware to be an-

nealed through an elongate lehr tunnel having a heated section and a cooling section, generating products of combustion in the heated section of the lehr tunnel in such manner that the products of combustion will envelop the ware passing through the tunnel, introducing air under pressure into the cooling portion of the lehr tunnel in such manner as to induce an inflow of atmospheric air into the exit end thereof, controllably venting air from the cooling section of the tunnel to the atmosphere at intervals therewith, so regulating the amount of air introduced into the tunnel under pressure and the amount of air induced into the tunnel at the exit end in respect to the amount of air vented from the cooling section of the tunnel to the atmosphere as aforesaid as to cause said products of combustion to flow along within said tunnel to the end thereof through which the ware enters, and venting said products of combustion from the tunnel to the atmosphere at said end.

9. The method of annealing glassware, comprising the steps of passing the ware through an elongate tunnel lehr including a tunnel having an opening through which ware enters, generating products of combustion in said tunnel below the path of the ware therethrough, and continuously directing a part of said products of combustion to and through said opening to the atmosphere in an upwardly inclined direction and with a velocity such as substantially to prevent inflow of atmospheric air into the lehr tunnel through said opening.

10. Apparatus for annealing glassware, comprising an elongate tunnel having a heating portion, open work conveying means for moving glassware through said tunnel, and a burner for generating transverse recirculations in said tunnel, said burner being located in said portion of said tunnel below the path of the ware therethrough and disposed to direct flames toward both lateral side walls of the tunnel, the region of said burner being open to the interior of the tunnel above said burner.

11. Apparatus in accordance with claim 10 wherein a plurality of burners are provided disposed at spaced intervals along said portion of the tunnel and similarly arranged to said burner of claim 10 to provide recirculation of the gases in the tunnel, and wherein said burners are provided with separate chambers for the burner openings directed toward the opposite side walls of the tunnel respectively, separate fuel supply means for the chambers of said burners supplying fuel toward opposite sides of said tunnel respectively, and independent adjusting means for each of said fuel supply means for effecting differential control of the circulations on opposite sides of the median central portion of the tunnel for differentially controlling the temperature gradients to which ware passing through the tunnel on the conveying means on opposite sides of the center line thereof is subjected.

12. Apparatus for annealing glassware, comprising an elongate tunnel having a heating portion, open work conveying means for moving glassware through said tunnel, and a plurality of groups of burners for generating transverse recirculations in the tunnel, said burners being located at spaced intervals along said portion of the tunnel below the path of the ware for directing flames generally toward the side walls of said tunnel, certain burners of each group being directed at acute angles to the longitudinal axis

5 of said tunnel and inclined toward the forward end of said tunnel and other burners of each group being at acute angles to the longitudinal axis of said tunnel and directed toward the rear thereof, the region of each of said burner groups being open to the interior of the tunnel above said burner groups.

13. Apparatus in accordance with claim 12, wherein passage-forming means are associated with the burners of each group for directing flames and gases induced by the burners from the region of the burners toward the side walls of said tunnel and for assisting in the inductive recirculation of the gases in the tunnel by the burners.

14. Apparatus for annealing glassware, comprising an elongate tunnel, means for conveying glassware therethrough, a burner located in said tunnel below the path of the glassware therethrough, and comprising a burner structure supported adjacent to the center of the tunnel at the bottom thereof, interengaging means between said burner structure and its support for accurately positioning the burner at the desired point, a pipe rigidly connected to said burner structure 20 for supplying it with a combustible medium, means facilitating the easy removal of the burner structure for cleaning, replacement or repair, including a removable side wall portion for the lehr tunnel including a part removable with said 25 pipe and another part removable independently of said pipe, and flame directing structure intermediate said burner structure and the side wall of the tunnel through which said pipe extends, including an opening above and in alignment with 30 said pipe, the burner being removable by first taking out the independently removable side wall portion, then tilting upwardly the burner structure and its associated pipe to disengage the burner from its positioning means in respect to its subjacent support, then laterally removing the burner by said pipe.

15. Apparatus for annealing glassware, comprising an elongate tunnel, openwork conveying means for moving glassware therethrough, a plurality of burners disposed at intervals across said tunnel below the path of the ware and arranged to direct flames toward the end of the tunnel through which the ware enters from points spaced a predetermined distance from said end, passage means associated with said burners for directing a part of the flames thereof into said tunnel adjacent to said end thereof, other passage means communicating between the region of said burners and the underside of said conveying means, whereby a part of the products of combustion from said burners will be recirculated in paths generally longitudinal of the tunnel by the inductive action of said burners, and means for effecting a differential control of said burners for differential control of the temperatures to which the ware is subjected laterally of said tunnel.

16. Apparatus for annealing glassware, comprising an elongate tunnel, open-work conveying means for moving glassware therethrough, a plurality of burners located at spaced intervals across said tunnel below the path of the ware therethrough and arranged to direct flames toward the end of the tunnel through which the ware enters from points spaced a predetermined distance from said end, Venturi passage means respectively for the flames of each of said burners and opening at the forward end of the tunnel partially to the interior thereof, a part of the top of said passage means adjacent to said burners being of refractory tile and the remainder of the

upper portions of said passage means being of material of good heat conductivity to absorb and radiate heat to the ware entering the tunnel, and other passage means communicating between the region of said burners and the underside of said conveying means, whereby a portion of the products of combustion of said burners will be recirculated by the inductive action thereof in paths extending longitudinally of said tunnel in the entering end zone thereof.

17. Apparatus for annealing glassware, comprising an elongate tunnel, conveying means for moving glassware therethrough, a burner in said tunnel below the path of the ware and arranged to direct flame toward the end of the tunnel through which the ware enters from a point spaced a predetermined distance from said end, passage forming means associated with said burner for directing the flames thereof toward the said end of the tunnel so that the products of combustion may be introduced into the tunnel and also exhausted therefrom at said end thereof, and an adjustable damper associated with the end of said passage forming means adjacent to said end of the tunnel for controlling the proportion of said products of combustion vented through said end of the tunnel and the complementary portion thereof directed into the tunnel to flow therewith in the same direction as the movement of the ware therethrough.

18. Apparatus for annealing glassware, comprising an elongate tunnel, conveying means for moving glassware therethrough, means to supply products of combustion to said tunnel below the path of the glassware and to direct said products of combustion toward the end of the tunnel through which the ware enters from a point spaced a predetermined distance from such end, means extending transversely of said tunnel for conducting said products of combustion from said supply means toward said end of the tunnel, the last named means communicating with the interior of the tunnel at said end, a plurality of independently mounted dampers in said last named means arranged transversely of said end of the tunnel for deflecting gases back into the tunnel and for controlling the proportion of the products of combustion so deflected back into the tunnel to flow therewith in the same direction as the movement of the ware therethrough, means for venting the remainder of the products of combustion to the atmosphere at said end of the tunnel, and means for substantially independently adjusting the position of said dampers to effect a transverse control of the products of combustion recirculated in the entering end of the tunnel.

19. Apparatus for annealing glassware, comprising an elongate tunnel having a heating portion and a cooling portion, means for conveying glassware therethrough, a jet nozzle in the cooling portion of said tunnel for introducing a cooling medium under pressure into the tunnel, said jet nozzle being so disposed and directed as to cause a circulation of tunnel atmosphere in a path having a major component of direction transverse of said tunnel, a deflector associated with one wall of said tunnel and arranged to be impinged by the cooling medium from said jet nozzle said deflector being spaced from its associated wall to provide a passageway therebetween into which some of the cooling medium and tunnel atmosphere circulated by said jet nozzles may pass, and an exhaust passage connecting said passageway with the atmosphere outside the tunnel for venting from the tunnel cooling medium and

tunnel atmosphere passing through said passageway.

20. Apparatus for annealing glassware, comprising an elongate tunnel, open-work conveying means for moving glassware therethrough, opposing jet nozzles located adjacent to the upper corners of said tunnel and directed generally toward the center thereof above the path of the ware, means for supplying a cooling medium under pressure to said jet nozzles, deflector means associated with the roof of said tunnel substantially along the longitudinal center line thereof and so positioned as to be impinged by the tunnel atmosphere circulated by said jet nozzles and to direct the circulation in the tunnel from the jet nozzles downwardly in the longitudinal central portion of the tunnel, said deflector means being spaced from the roof of said tunnel to provide passageways between the upper edge portions of the deflector means and the roof of the tunnel, and passage means connecting said passageways with the atmosphere outside the tunnel for venting a portion of the circulated tunnel atmosphere from the tunnel.
21. Apparatus for annealing glassware, comprising an elongate tunnel, means for conveying glassware therethrough, a jet nozzle in the cooling portion of said tunnel for introducing a cooling medium under pressure into the tunnel, said jet nozzle being so disposed and directed as to cause circulation of tunnel atmosphere in a path having a major component of direction transverse of said tunnel, a deflector associated with one wall of said tunnel and so positioned as to be impinged by the cooling medium from said jet nozzle, said deflector being spaced from its associated wall to provide a passageway facing said jet nozzle, adjustable means for controlling the width of said passageway, and an exhaust passage connecting said passageway with the atmosphere for venting from the tunnel cooling medium in tunnel atmosphere passing through said passageway.
22. Apparatus for annealing glassware, comprising an elongate tunnel, opposing jet nozzles arranged in the upper corner portions of said tunnel for directing cooling medium under pressure into said tunnel above the path of the ware therethrough, independently adjustable means for supplying cooling medium under pressure to said jet nozzles, a trough-shaped deflector associated with the roof of said tunnel and so positioned as to be impinged by said jet nozzles, said deflector being spaced from the roof of said tunnel to provide passageways to the space within the deflector said jet nozzles and said deflector cooperating to cause an induction circulation of tunnel atmosphere from the jet nozzles to the deflector, downwardly in the central portion of said tunnel, laterally to the sides thereof, and thence upwardly to be recirculated by said jet nozzles, individually adjustably mounted portions of said deflector adjacent to the roof of the tunnel on the sides of said deflector for adjustably controlling the width of said passageways intermediate the upper edges of said adjustable deflector portions and the roof of the tunnel, and an exhaust passage connecting said passageways and the interior of said trough-shaped deflector with the atmosphere for venting from the tunnel a portion of the circulated tunnel atmosphere, the amount of which is regulated by the adjustment of the adjustable portions of said deflector, whereby independently adjustable circulations of tunnel atmosphere may be maintained on oppo-

site sides of the longitudinal center line of the tunnel at the region at which the above recited elements are located.

23. Apparatus for annealing glassware, comprising an elongate tunnel, open-work conveying means for moving glassware therethrough, opposed jet nozzles disposed in the upper corner portions of the tunnel for introducing a cooling medium under pressure thereinto and in directions generally toward the longitudinal center line of the tunnel, a trough-shaped deflector member disposed in fixed position centrally of the roof portion of the tunnel intermediate said jet nozzles so as to be impinged by the tunnel atmosphere circulated thereby, said jet nozzles and said deflector member cooperating to cause a circulation of tunnel atmosphere by the inductive action of said jet nozzles toward the deflector member, thence downwardly through the ware and through the conveying means, thence laterally toward the side walls of the tunnel and thence upwardly to be recirculated as aforesaid, said deflector member having hinged portions at the sides thereof and forming a part of the deflecting surfaces thereof, said hinged portions defining adjustable width passageways between themselves and the roof of the tunnel into the interior of said trough-shaped deflector member, an exhaust port connecting the interior of said deflector member with the atmosphere outside the tunnel, and a common means for simultaneously controlling the position of said hinged portions of said deflector member to control the width of said passageways and thereby to control the amount of the circulated atmosphere in the tunnel which is vented from the tunnel through such passageways and said port.

24. Apparatus for annealing glassware, comprising an elongate tunnel, means for conveying glassware therethrough, a pipe extending longitudinally of said tunnel at each of the upper corners thereof, a plurality of jet nozzles associated with each of said pipes and all directed in a substantially horizontal plane transversely of said tunnel and generally toward the longitudinal center line thereof, a substantially continuous hollow, trough-shaped deflector associated with the roof of said tunnel and extending along the longitudinal center line thereof and positioned so as to be impinged by the tunnel atmosphere circulated by the inductive action of said jet nozzles, the upper edges of said deflector being spaced from the roof of said tunnel on either side thereof to provide passageways into the interior of said deflector, means dividing the interior of said deflector into independent substantially contiguous zones, exhaust passages connecting the interior of said deflector in each of said zones with the atmosphere outside the tunnel, and means associated with each of said exhaust passages for controlling the amount of circulated tunnel atmosphere vented from the tunnel.

25. Apparatus for annealing glassware, comprising an elongate tunnel, open-work conveying means for moving glassware therethrough, a pipe extending along each of the upper corners of said tunnel in the cooling portion thereof, means for supplying air under pressure to said pipes, a plurality of jet nozzles associated with each of said pipes all of which are disposed in a substantially horizontal plane and certain at least of which have their axes inclined at an acute angle to the longitudinal axis of the tunnel, a substantially continuous trough-shaped deflector having

upper side portions associated with the roof of the tunnel in the zone in which said jet nozzles are located and providing between itself and the roof a duct for tunnel atmosphere, means dividing said duct into a plurality of substantially contiguous zones, exhaust ports connecting the duct in each of said zones with the atmosphere, the upper side portions of said deflector being spaced a predetermined distance from the roof of said tunnel in at least one of said zones to provide openings or passageways therebetween communicating between the interior of said tunnel and said duct, damper means associated with the exhaust port of the portions of the duct continuously open to the tunnel as aforesaid, certain other portions of said deflector having adjustably mounted wall sections providing adjustable width openings or passageways intermediate the tunnel and the part of the duct within the deflector at these portions, and means accessible from the exterior of the annealing apparatus for adjusting such adjustable wall sections, said jet nozzles and said deflector cooperating to cause a recirculation of the tunnel atmosphere in the cooling portion of the tunnel.

26. Apparatus for annealing glassware, comprising an elongate tunnel including a heated portion and a cooling portion, means for conveying glassware therethrough, substantially laterally directed jet nozzles in the cooling portion of said tunnel, means for supplying a cooling medium under pressure to said nozzles, deflector means in said tunnel disposed so as to be impinged by the jets from said nozzles, and means for controlling the angular position of the jets from said nozzles in respect to the surfaces of said deflector means against which these jets impinge in such a way as to control the longitudinal component of the direction of flow of the gaseous media deflected from said surfaces, and thereby controlling the inflow of atmospheric air into the exit end of said tunnel.

27. Apparatus for annealing glassware, comprising an elongate tunnel including a heated portion and a cooling portion, means for conveying glassware therethrough, longitudinally extending pipes in the upper corners of the cooling portion of said tunnel, substantially laterally directed jet nozzles at spaced intervals along said pipes, means for supplying cooling air under pressure through said pipes and to and through said nozzles, a longitudinally extending deflector associated with the roof of said tunnel in the cooling portion thereof and positioned to be impinged by the jets from said nozzles, said nozzles and said deflector cooperating to set up in the cooling portion of the tunnel induction circulations from the jet nozzles generally toward the center of said tunnel above the path of the ware, downwardly adjacent to the longitudinal center portion of the tunnel and between the articles moving therethrough, thence laterally toward the side walls and upwardly along both side walls, and means associated with the above recited elements for controlling the inflow of atmospheric air into the exit end of said tunnel.

28. Apparatus for annealing glassware, comprising an elongate tunnel including a heated portion and a cooling portion, means for conveying glassware therethrough, a pipe extending longitudinally of the cooling portion of said tunnel, a jet nozzle carried by said pipe, means for supplying a cooling medium under pressure through said pipe to said nozzle, a deflector in said tunnel disposed so as to be impinged by the jet from said nozzle, an inclined deflecting vane associated with said jet nozzle, carried by said deflector and extended toward said nozzle, and means mounting said pipe and said nozzle for rotative adjustment about the longitudinal axis of said pipe, said vane being so constructed and arranged as to deflect gaseous media in one direction or the other longitudinal of the tunnel and in differing amounts in accordance with the rotated adjusted position of said pipe and said jet nozzle.

29. The method of annealing glassware, which comprises the steps of passing the ware to be annealed through an elongate lehr tunnel having a heated section and a cooling section, introducing heated gases in the tunnel from points below the level of the path of the ware therethrough and in such manner and direction as to cause recirculation of the tunnel atmosphere in orbital paths in the heated section of the tunnel by energy derived from the velocity of the gases thus introduced and in such manner and direction that the recirculated gaseous media in the tunnel will flow toward the sides of the tunnel at a level below the path of the ware, thence up the sides of the tunnel, toward the center thereof above the path of the ware, and thence downwardly through the path of the ware and spaced from the sides of the tunnel.

DONALD G. MERRILL.
